[57] CLAIM

The ornamental design for a combined baker's rack and organizer, as shown and described.

DESCRIPTION

FIG. 1 is a perspective view of a combined baker's rack and organizer showing a first embodiment of our new design; FIG. 2 is a front elevational view thereof; FIG. 3 is a right side view thereof; FIG. 4 is a top plan view thereof; FIG. 5 is a bottom view thereof; FIG. 6 is a perspective view of a combined baker's rack and organizer showing a second embodiment of our new design; FIG. 7 is a front elevational view thereof; FIG. 8 is a right side view thereof; FIG. 9 is a top plan view thereof; FIG. 10 is a bottom view thereof; FIG. 11 is a perspective view of a combined baker's rack and organizer showing a third embodiment of our new design; FIG. 12 is a front elevational view thereof; FIG. 13 is a right side view thereof; FIG. 14 is a top plan view thereof; and, FIG. 15 is a bottom view thereof. The rear elevational and left side views of each embodiment are the same as the front elevational and right side views, respectively.
